TOOL HANDLE ATTACHING AND SHOCK-
ABSORBING MEANSEdward M. Holfeiner, Columbus, Ohio, assignor
to The Ohlen-Bishop Company, Columbus,
Ohio, a corporation of Ohio

Application July 2, 1936, Serial No. 88,575

4 Claims. (Cl. 145—108)

My invention relates to tool handle attaching and shock-absorbing means. It has to do more particularly with means for securing a tool blade, such as a saw blade, in a handle and with means for absorbing shocks which result from using the blade and to substantially prevent such shocks from reaching the handle. Although I shall describe my invention as particularly applicable to a saw, it is to be understood that it is not limited thereto.

In the ordinary handsaw, one end of the metal blade is inserted in a slot in a handle made of wood or the like and is secured in the handle by means of screws or rivets. The screws are initially tightened to such an extent that the blade will be tightly gripped in the handle. However, when the wood of the handle contracts, due to changes in moisture conditions, the screws become loose and therefore the blade becomes loose in the handle. This looseness is made more pronounced because of the fact that the holes in the saw blade through which the screws pass must be made slightly larger than the diameter of the screws so as not to injure the threads on the screws. At a later period, the wood of the handle may again expand to such an extent that the handle will again be tight on the blade. In fact, it may expand to such an extent that the screws will be so tight that cracking of the handle will result. These screws are usually made in two pieces, and when the handle contracts so that they become loose there is danger that the head of the screw will fall off due to the fact that the vibration resulting from use of the tool will cause it to rotate.

Another disadvantage of saws and other similar tools made heretofore resides in the fact that there has been no means provided for absorbing the shock transmitted from the blade to the handle during use of the tool. These shocks transmitted to the handle cause fatigue and may even cause some injury to the hand of the workman using the tool.

One of the objects of my invention is to provide a tool of the type indicated embodying a blade and a handle member, the blade being secured to the handle member by means of screws, rivets, or similar securing means, means also being provided to compensate for expansion and contraction of said handle and to prevent the screws or similar means from becoming loose thereby causing the handle to be firmly secured to the blade at all times.

Another object of my invention is to provide a tool of the type indicated embodying a blade

and a handle secured together in the manner indicated wherein means is provided for absorbing the shocks resulting when the blade is used and for substantially preventing them from reaching the handle.

In its preferred form my invention contemplates the provision of a tool embodying a blade having one end that fits in a recess formed in a handle member of wood or the like. The blade is secured in the recess in the handle member by means of screws which pass transversely through corresponding openings formed in the handle member and the end of the blade. Resilient material is preferably disposed between the blade and the wall of the recess formed in the handle in which it is inserted. This resilient material is adapted to compensate for expansion and contraction of the handle in order that the blade will always tightly fit within the recess and is adapted to absorb shocks which are imparted to the blade. The screws are surrounded with resilient material so that the metal blade will not contact with the metal screws but, on the other hand, there will be a resilient cushion between these members which will serve to absorb shocks imparted to the blade. However, the resilient material surrounding the screws serves also to compensate for expansion and contraction of the handle and to maintain the screws tight at all times.

The preferred embodiment of my invention is illustrated in the accompanying drawing wherein similar characters of reference designate corresponding parts and wherein:

Figure 1 is a perspective view partly broken away showing a portion of a handsaw blade with a handle applied thereto according to my invention.

Figure 2 is a section taken substantially along line 2—2 of Figure 1.

Figure 3 is a plan view of a member adapted to be inserted in the blade-receiving recess formed in the handle.

Figure 4 is a perspective view of a member adapted to be inserted in a screw-receiving opening.

With reference to the drawing, I have illustrated a handsaw embodying a blade 1 and a handle member 2 of usual construction. The blade 1 has its end inserted in a recess or open-ended slot 3 formed in the handle 2 in the usual manner. In order to secure the blade in the slot formed in the handle a plurality of transversely extending screws 4 are provided. These screws pass through corresponding openings 5 and 6 formed in the handle and the blade respectively.

It will be noted from the drawing that between the blade 1 and the walls of the slot 3 is disposed a cushion of material 7. This material may be of any suitable flexible material, preferably 5 resilient, for example, rubber. It will be noted that the material 7 extends over the side surfaces of the blade and even around the rear edge thereof. In other words, there is a resilient cushion 10 between the blade 1 and all the walls of the slot 3 so that the blade will not be in direct contact with the handle at any point. The rubber cushion 7 is 15 preferably of such thickness that when the blade is inserted in the handle it will be necessary to compress the rubber cushion. Thus, if the handle member 2 contracts or shrinks so that the slot 20 3 will become larger, the rubber cushion 7 will expand to compensate for this contraction of the handle and will maintain a tight fit between the blade and the handle. On the other hand, if the handle expands and thereby makes the slot 3 smaller, it will not be cracked or otherwise injured because the rubber cushion 7 will be compressed. Obviously, the rubber cushion will 25 absorb the shocks imparted to the blade 1 during the use of the saw, and will substantially prevent said shocks from reaching the handle 2.

Each of the screws 4 embodies a screw portion 3 having a head 9 and a threaded end 10 and a nut portion 11 embodying a head 12 and a tubular portion 13 which is threaded onto the threaded end 10 of the screw portion 8. In order to provide 30 means for substantially preventing the shocks imparted to the blade 1 from being transmitted to the screws 4 and thence to the handle and in order to prevent the screws from coming loose at any time I provide a member 14 which surrounds each screw. This member 14 is preferably made of 35 the same material as the cushion 7. The resilient member 14 entirely surrounds the shank of the screw portion 8 of the screw. The outer surface of this member 14 (Figure 2) gradually tapers inwardly towards the inner end thereof so that the member is of substantially frusto-conical form. Ribs 16 are provided on the screw portion 8 to 40 prevent rotation of the member 14 thereon, the ribs extending into the material of the member 14. The walls of the openings 5 in the handle 2 are tapered the same as the tapered outer surface of the member 14. It will be noted that the 45 resilient member 14 extends a considerable distance inwardly past the point 17 where the threads on the member 8 terminate. It will also be noted that the extreme inner end of the member 14 is bevelled as at 18, the bevel extending towards the center of the screw and outwardly 50 towards the head 9.

The member 14 is preferably molded on the screw portion 8. The screw portion 8 carrying member 14 is inserted in the openings 5 of the handle and will extend through the opening 6 in the blade. It will be noted that the member 14 will extend entirely through the blade. The member 14 is preferably of such thickness that it must be compressed when it is placed in the openings 5 and 6. The nut portion 11 of the screw is then threaded on the threaded end 10 of member 8. The member 14 is of such a length that before the screw is tight in the handle, the end of the tubular portion 13 of the nut thereof will contact with the bevelled end 18 of the member 14. This bevel 18 is in such a direction that upon tightening of the nut 11 on the screw portion 8, the material of the member 14 will be forced outwardly away from the center of the screw so that it will contact firmly with the wall of 55

the opening 6 formed in the blade 1 and also with the walls of openings 5. The member 14 will thus be compressed. Furthermore, the head 9 on screw portion 8 will tend to force the member 14 inwardly when the screw is tightened. This will 5 force the member 14 tightly in contact with the walls of the opening 5, due to the corresponding taper of the outer surface of member 14 and the walls of openings 5. Also, the head 9 pressing inwardly on the outer end of member 14 will aid 10 in forcing the member 14 tightly into contact with the wall of opening 6 in the blade.

It will be apparent that because the member 14 is compressed when the screw is initially tightened, if the handle 2 contracts or shrinks, thereby causing openings 5 to become larger, the member 14 will expand to compensate for contraction of the handle. Consequently, the screw will always be tight in the handle. On the other hand, if the handle expands, thereby causing openings 20 5 to become smaller, the material of the member 14 will further compress and no injury to the handle will result. The inner end of the tubular portion 13 of the head of the screw will always bear against the end of member 14 firmly so that 25 there will be no danger of accidental turning and loosening of the head portion of the screw. If the handle expands to an unusual extent so that the heads 9 and 12 bear on the handle with unusual force, the resilient member 7 will compress to such an extent as to prevent splitting of the handle. The resilient tubular member 14 also serves as a cushion element to prevent shocks 30 being transmitted from the blade 1 through the screw and thence to the handle member.

In Figure 3, I illustrate a structure which will facilitate insertion of the rubber insert into slot 3. This structure comprises a resilient member 7a, which is the same as member 7, but which is secured to a U-shaped member 7b formed of resilient metal. The member 7a may be secured to member 7b in any suitable manner such as by vulcanizing. It will be apparent that because the resilient member 7a is secured to the metal member 7b, which surrounds member 7a, it will facilitate insertion of member 7a in the slot 3.

In Figure 4, I show a modified resilient structure for surrounding each of the screws 4. This structure embodies a resilient member 14a which is the same as member 14. However, this member 14a is substantially surrounded by a member 14b of substantially frusto-conical form which is made of resilient metal. A slot 14c is formed in the member 14b. This composite structure will surround each of the screws 4, in the same manner that member 14 surrounds a screw. The fact that member 14b, which is made of metal, surrounds resilient member 14a, facilitates insertion of the member in the openings 5 and 6. Also, since this metal member 14b will extend through opening 6 in the blade 1, it will protect member 14a from any danger of being cut by the blade 1. The slot 14c in metal member 14b will permit expansion and contraction of member 14b at the time that the resilient member 14a expands and contracts.

It will be apparent from the above that I have provided a tool embodying a blade which is inserted in a recess in a handle portion and held therein by screws or similar securing means, the tool being provided with means for effectively preventing the handle member from becoming loose on the blade and for preventing loosening of the securing means. This means also func- 70 75 75

tions to cushion the handle against shock imparted to the blade.

Although I have described this invention as being particularly applicable to ordinary hand-saws it will be apparent that it is applicable to any of the various types of saws which are provided with handles. Furthermore, it is not limited in its application to saws. It may be applied to any tool wherein a blade or similar member 10 is held in a handle member by means of screws, rivets or similar securing means.

Many other advantages will be apparent from the preceding description, the drawing and the following claims.

15 Having thus described my invention, what I claim is:

1. In a tool of the type described, a blade member made of metal, a handle member, the blade having a portion fitting into a recess formed in 20 said handle member, an insert of resilient material between all of the surfaces of said recess and the adjacent surfaces of said blade, said insert of resilient material being of such thickness that it is compressed when the blade is positioned in 25 such recess, a plurality of screws for securing the blade in said recess extending transversely through aligning openings formed in said blade and said handle member, each of said screws embodying a screw portion and a nut portion, said 30 screw portion embodying a head and a shank which is threaded at its inner end, said nut portion embodying a head and an internally threaded tubular portion adapted to be screwed onto the threaded end of the screw portion, a member 35 formed of resilient material disposed in surrounding relation to the screw portion, said member having a tapered outer surface which cooperates with a correspondingly tapered surface on the wall of the opening in the handle member in which it is disposed, said resilient member extending inwardly past the point on the screw portion where the threads terminate, the extreme inner end of said resilient member having a conical depression 40 therein forming a bevelled edge, said resilient member being of such length that the inner end of the nut portion of the screw will contact with the bevelled end thereof before the screw is completely tightened.

2. In a tool of the type described, a blade member, a handle member, means for securing the blade member to the handle member, said means comprising screws which extend through aligning openings in said handle member and blade member, each of said screws embodying a screw portion 50 and a nut portion, said screw portion embodying a head and a shank which is threaded at

its inner end, said nut portion embodying a head and an internally threaded tubular portion adapted to be screwed onto the threaded end of the screw portion, a member formed of resilient material disposed in surrounding relation to the screw portion, said member having a tapered outer surface which cooperates with a correspondingly tapered surface on the wall of the opening in the handle member in which it is disposed, said resilient member extending inwardly past the point on the screw portion where the threads terminate, the extreme inner end of said resilient member having a conical depression therein forming a bevelled edge, said resilient member being of such length that the inner end 10 of the nut portion of the screw will contact with the bevelled end thereof before the screw is completely tightened.

3. In a tool of the type described, a blade member, a handle member, means for securing the blade member to the handle member, said means comprising screws which extend through aligning openings in said handle member and blade member, each of said screws embodying a screw portion and a nut portion, said screw portion embodying a head and a shank which is threaded at its inner end, said nut portion comprising a head and a tubular extension which is internally threaded and is adapted to be screwed onto the threaded shank of the screw portion, a member 20 formed of non-metallic inherently resilient material disposed in surrounding relation to the main portion of the screw and adapted to extend through the opening in the blade, said resilient member extending inwardly past the point on the screw portion where the threads terminate, the extreme inner end of said resilient member having a conical depression therein forming a bevelled edge, said resilient member being of such length that the inner end 25 of the nut portion of the screw will contact with the bevelled end thereof before the screw is completely tightened.

4. In a tool of the type described, a tool member, a handle member, means for securing the tool member and the handle member together, said means comprising securing members which extend through aligning openings in said handle member and tool member, and a member formed of non-metallic inherently resilient material disposed in surrounding relation to each of said securing means, said member being substantially surrounded by a resilient member formed of metal, said metal member being adapted to contact with the edge of the cooperating opening in the tool member and being adapted to protect said non-metallic material.

EDWARD M. HOLFELNER.
